UNITED STATES PATENT OFFICE.

JOHN A. FITZPATRICK, OF CARRICK BOROUGH, PENNSYLVANIA.

BOAT-PROPELLER.

1,264,282.

Specification of Letters Patent. Patented Nov. 12, 1918.

Application filed July 18, 1916. Serial No. 110,060.

To all whom it may concern:

Be it known that I, JOHN A. FITZPATRICK, a citizen of the United States, and a resident of Carrick Borough, in the county of 5 Allegheny and State of Pennsylvania, have invented a certain new and useful Improvement in Boat-Propellers, of which the following is a specification.

My invention is an improvement in boat 10 propellers of that type in which blades are attached to rotating shafts projecting laterally from the sides of a boat and below the water line.

The details of construction, arrangement 15 and operation are as hereinafter described, and illustrated in the accompanying drawing, in which:

Figure 1 represents a side elevational view of a vessel equipped with propellers 20 constructed according to my invention.

Fig. 2 represents a front elevational view thereof.

Fig. 3 represents a view in section taken 25 transversely through the vessel, showing one of the propellers partially in section.

Fig. 4 represents a view in section taken transversely on the line 4-4 of Fig. 3.

Fig. 5 represents a view in section taken transversely on the plane indicated by the 30 line 5-5 of Fig. 3.

Fig. 6 represents a view in perspective of a propeller constructed according to my invention.

The propellers as indicated in Figs. 1 35 and 2, are mounted on the sides of the vessel at suitable points, any desired number of the propellers being utilized. As the propellers are all constructed in a similar manner, description of one will suffice for all.

Each of the propeller mechanisms 40 includes a bearing 5 extending laterally through the side of the ship, having a plate 6 which rests against the outer side of the hull. A suitable plate 7 may be mounted 45 on the bearing against the inner side of the hull and suitably secured both to the bearing and to the hull, if necessary, the object of the plates 6 and 7 being to strengthen the bearing and to provide a watertight 50 joint around the same.

The bearing is provided with a bore extending longitudinally therethrough, the outer portion of which is enlarged as at 8 and receives the enlarged outer end 9 of a 55 power shaft 10. The latter may be driven from any suitable source of power. A col-

lar 11 or equivalent means, mounted on the shaft 10, within bearing 5, serves to prevent longitudinal movement of said shaft relatively to the bearing.

The outer portion of enlargement 9 of shaft 10, beyond the outer end of bearing 5 is transversely bored to rotatably receive a rod 12. The latter has mounted at its ends the blades 13. The latter are set at right angles to each other, as clearly indicated in the drawings. The blades and rod 12 may, if desired, be formed of a single piece of metal, or the blades may be made separately and subsequently attached to the rod in any suitable manner. As the shaft 10 is rotated, the rod 12 turns with it, and at the same time said rod 12 is free to rotate with respect to the axis of said shaft 10.

The outer end of bearing 5 is formed with 75 a cam face or surface at 14 which surface for the main part lies in a plane at right angles to the axis of shaft 10. The cam surface, however, at diametrically opposed points on a line extending parallel with the 80 water line of the vessel, is provided with depressions as at 15, which depressions are substantially V-shaped, and are of such dimensions as to receive the corners of a rectangular block 16 fixedly mounted on the 85 rod 12 to one side of the end of shaft 10. As the rod 12 turns under the influence of the shaft 10, one side of the block 16 rides against the cam face 14, and it will be noted that when one of the depressions has 90 been reached, the rod may be turned a quarter revolution as the corner of the block passes the depression 15.

Means for automatically turning said rod at these intervals includes a pinion 17 fixedly 95 mounted on rod 12 adjacent block 16 and having four teeth 18 each of which is situated centrally of one side of the block and projects beyond that side a slight distance. On opposite sides of each of the depressions 100 15 in the cam surface 14 are mounted the members of a pair of teeth 19, which teeth are adapted to coöperate with the teeth 18 of cam 17 in effecting the automatic and intermittent rotation of the rod 12. As the 105 shaft 10 rotates, the teeth 18 on the cog will periodically engage with one of the teeth 19, so as to effect the quarter revolution of the rod 12, and this action will take place whether the propeller is being driven in a 110 forward or in a reverse direction, whereby it will be seen that at all times the lower blade

13, or that one which is delivering the force of the stroke, will be set at right angles with the line along which it is being forced through the water, while the upper blade 5 will be set parallel with that line and thus offer a small amount of resistance as it cuts through the water.

At the time the cog teeth strike the teeth 19, one of the corners of the block 16 will 10 be in position to move into one of the depressions 15, as the rotation of the shaft 10 continues, so that no resistance will be offered to the partial rotation of the rod 12. However, at the points intermediate 15 the depressions 15, one of the edges of the block 16 rides against the base of the cam 14, and thus prevents rotation of the rod. It will of course be understood that if desirable the block 16 and cog wheel 17 may 20 be cast integrally or formed integrally with the rod 12, and similarly the cam 14 and teeth 19 may be cast or formed integrally with the bearing. The portions of the bearing which project without the vessel are 25 tapered at front and rear, as indicated at 20, so as to offer a minimum degree of resistance to the water.

The rod 12 on the side of shaft 10 opposite the block 16, is equipped with a suitable sleeve or shoulder 21, to prevent longitudinal movement of the rod 12 through the shaft. This shoulder or sleeve does not, however, interfere with the rotary movement of the rod relatively to the shaft.

Such a propeller as I have provided will 35 be found to give a maximum degree of power whether fully or whether half submerged, since the returning blade meets little or no resistance by reason of the fact 40 that it cuts edgewise through the water or air as the case may be, while the lower blade or that one delivering the stroke is forced through the water at right angles to the line of movement. One of the many advantages of my propeller is that a great 45 number of them may be mounted on the sides of a vessel, and may be driven in unison in effecting the propulsion of said vessel at great speed. One of the draw- 50 backs of the use of ordinary stern propellers

is that the number of them which may be used on any one vessel is greatly limited.

Any suitable method for lubricating the various moving parts of the device may be employed. I have as a suggestion for a 55 method by which the rod 12 may be lubricated, shown in Fig. 3, the shaft 10 as being provided with a duct 22 which leads to the rod 12 from the bearing 5 so that the oil from the bearing may be fed to said rod at 60 its bearing point with the shaft.

I claim:—

1. The combination with a vessel, of a propeller including a bearing attached to the side of the vessel, a power shaft rotatably extending through the bearing and having at its outer end an enlargement rotatably bearing against the said bearing, a rod journaled transversely through the enlargement and provided with blocks set at 70 right angles to each other, a rectangular block fixed on the rod on one side of the enlargement and bearing against the enlargement for holding the rod against longitudinal displacement in one direction, a 75 shoulder on the rod bearing against the enlargement on its opposite side for holding the rod against longitudinal displacement in an opposite direction, a circular cam on the bearing surrounding the power shaft 80 against which the block bears and with which the block coöperates in controlling the rotation of the rod, a gear wheel mounted on the rod above the block, and means on the bearing beyond the cam with 85 which the gear wheel coöperates in effecting intermittent rotation of the rod.

2. The combination with a vessel of a bearing attached to the side of the vessel below the water line and having its outer portion projecting a distance beyond the vessel, a propeller supported in the bearing and arranged at the outer end of the bearing whereby to be spaced from the side of the vessel, the outer portion of the bearing being tapered in both directions at front and rear to form cutting edges parallel with the water surface for holding a minimum of resistance, substantially as described. 95

JOHN A. FITZPATRICK.
